UNITED STATES PATENT OFFICE.

GERALD EDWARD BEER, OF ACTON, LONDON, ENGLAND.

DESIGN FOR A TOY ANIMAL.

Application filed June 12, 1924. Serial No. 9,865. Term of patent 3½ years.

To all whom it may concern:

Be it known that I, GERALD EDWARD BEER, a subject of the King of Great Britain, residing at Acton, London, England, have invented a new, original, and ornamental Design for a Toy Animal, of which the following is a specification, reference being made to the accompanying drawing, forming part thereof.

The figures are a front view and a side view of a toy animal showing my new design.

I claim:—

The ornamental design for a toy animal as shown.

GERALD EDWARD BEER.
